(57) **CLAIM**

The ornamental design for an operating handle for working vehicle, as shown and described.

DESCRIPTION

FIG. 1 is a front elevational view of an operating handle for a working vehicle showing our new design;

FIG. 2 is a back elevational view thereof;

FIG. 3 is a top elevational view thereof;

FIG. 4 is a bottom elevational view thereof;

FIG. 5 is a right side elevational view thereof;

FIG. 6 is a left side elevational view thereof;

FIG. 7 is a front perspective view thereof;

FIG. 8 is a back perspective view thereof;

FIG. 9 is a first referential view showing the operating handle of FIGS. 1-9 in reference to a working-vehicle operator's seat area;

FIG. 10 is a second referential view thereof; and,

FIG. 11 is a third referential view thereof.

The broken line depictions of a working-vehicle operator's seat, operating lever, and surrounding area are illustrative of environmental structure and form no part of the claimed design.

An article of the present design is an operating handle to be mounted at an operator's seat area of a working vehicle, such as a tractor; and is used, for example, for operating a front loader and the like.

1 Claim, 11 Drawing Sheets
